WASTE HEAT COKE OVEN

Carl Otto, New York, N. Y., assignor to Fuel Refining Corporation, Dover, Del., a corporation of Delaware

Application April 17, 1940, Serial No. 330,049

6 Claims. (Cl. 202—140)

The general object of the present invention is to provide a simple and effective coke oven battery which is similar in respect to its inclusion of horizontally elongated coking chambers alternating with heating walls, to the substantially standard type of by-product coke oven in which substantially all of the metallurgical coke used in the world is now produced, but which can be constructed at a substantially lower inherent cost per unit of volume of oven chamber space.

In my improved coke oven, the battery bulk and inherent cost of construction per unit of oven chamber space, is reduced materially by dispensing with regenerators, which, in one form or another, are now included in coke ovens of the standard type. In a preferred construction, however, my improved oven, while properly characterized as a waste heat oven, does include recuperative provisions for utilizing some of the available heat of the waste gases in moderately preheating the combustion air used in heating the ovens.

While not limited to such use, my improved oven was primarily devised for use in the practice of a method devised by me, for coking coals more volatile than are now used in the production of metallurgical coke, and more particularly for use in coking such coal in plants where there is no remunerative market or demand for the excess distillation gases not utilized in heating the coking chambers, and where it is practically important to keep the plant investment cost relatively low, at some sacrifice in operating efficiency and in the value of the by-products recovered from the gas.

In some cases, the ovens may be heated by the combustion of distillation gases passing directly from the oven chambers into the heating flues, and the excess distillation gases may be used in firing steam generating boilers for other plant purposes, without being subjected to any cleaning or by-product recovery process. I ordinarily consider it desirable, however, to recover the tar content of the distillation gases evolved, even where low plant investment is especially desirable, and precludes other by-product recovery.

My above mentioned process for coking high volatile coals requires relatively high oven temperatures, of the order of those used in the production of metallurgical coke, and an important specific object of the present invention is to provide simple and effective oven heating means which will not only furnish the relatively high oven heating effect required, but will give the uniform heat distribution essential for proper

coking and also essential to minimize the risk of injurious local overheating of the oven structure. My invention is characterized in particular by its provisions for supplying fuel gas and combustion air to vertical heating flues for the downflow of heating gases through each of said flues, and for the maintenance of a suitably long combustion zone in each flue.

The various features of novelty which characterize my invention are pointed out with particularity in the claims annexed to and forming a part of this specification. For a better understanding of the invention, however, its advantages, and specific objects attained with its use, reference should be had to the accompanying drawings and descriptive matter in which I have illustrated and described preferred embodiments of the invention.

Of the drawings:

Fig. 1 is a diagrammatic transverse sectional elevation of a coke oven battery, also showing associated charging and discharging apparatus;

Fig. 2 is a partial transverse section of the battery with its right hand portion taken on the line 2—2, and its left hand portion taken on the line 2A—2A of Fig. 3;

Fig. 3 is a partial longitudinal section of the battery shown in Fig. 1, with parts broken away, and with its right hand portion in section on the line 3—3 and its left hand portion in section on the line 3A—3A of Fig. 2;

Fig. 3B is a partial section on the line 3B—3B of Fig. 2;

Fig. 4 is a partial transverse section of a modified form of coke oven battery; and

Fig. 5 is a partial longitudinal section with its right hand portion taken on the line 5—5, and its left hand portion on the line 5A—5A of Fig. 4.

The coke oven structure shown in Figs. 1—3, 40 comprises horizontally elongated coking chambers A, having removable end doors A', and alternating with heating walls B, each heating wall including a row of side by side vertical heating flues C.

45 The mass of brickwork including the coking chambers A and heating walls B and the hereinafter mentioned channels and passages beneath the coking chambers and heating walls, is shown as supported on a reinforced concrete slab or deck member D, which forms the ceiling for a basement space underlying the coke oven structure, and which is supported on reinforced concrete pillars E.

Beneath each coking chamber is a horizontal 55 sole channel F extending between the opposite

sides of the battery and having an extension F' at one end for discharging waste gases into a waste heat tunnel G, extending longitudinally of the battery. Each of the heating flues C of a single heating wall has its lower end in communication with the sole channel F beneath the oven chamber immediately adjacent the heating wall at one side of the latter, through a vertical passage H in the brickwork beneath the heating wall and having a lateral outlet port H' opening to the corresponding sole channel F.

Combustion air is supplied to each combustion flue C through a corresponding channel I and a corresponding channel i, each formed in one of the flue division walls which extends transversely to the length of the heating wall. Each channel I opens to the corresponding flue C through one or more discharge ports I' intermediate the ends of the flue, one such port being shown and located at a level substantially below the top of the flue but somewhat nearer the top than the bottom of the flue. Each channel i opens to the corresponding flue at a higher level, through one or more outlet ports i'. In the preferred arrangement shown, the single outlet port i' from each channel i opens to the corresponding flue C substantially at its top.

Each of the channels I and i receives air at its lower end through a corresponding recuperator chamber or passage IA and ia, respectively, formed in the masonry beneath the heating walls and coking chambers. Each chamber or passage IA receives atmospheric air through a corresponding channel or passage IA' extending vertically upward through the deck D, and each passage or chamber ia receives atmospheric air through a passage ia' similar to the passage IA'. The relative rates of inflow to the different chambers IA and ia may be controlled by damper bricks, replaceable nozzles or other throttling devices, adjustably associated with the various channels IA' and ia'. Air passing upward through each of the recuperator chambers IA and ia, absorbs heat from the walls separating it from the adjacent waste heat sole channel F, and from each adjacent downflow channel H. To permit inspection and the ready removal of mortar or other obstructions, each of the channels I and i advantageously extends from the top to the bottom of the battery brickwork mass and supporting deck D, with each end normally closed by a suitable plug or other closure device.

As shown, fuel gas is passed down to the upper end of each flue C through a vertical gas supply conduit J, extending from the top of the flue to the top of the battery structure. Each conduit J may receive raw distillation gases through a corresponding inclined channel K and vertical channel K' directly from an adjacent coking chamber to the gas collecting space of which the channel K' opens at its lower end. Each channel K is inclined and has lower and upper ends respectively connected to the corresponding conduit and channel K'. As shown, the passage K' at one end of each oven chamber is connected to an ascension pipe L, and each of the other passages K' is provided with a removable closure K² at its upper end. The gas flow to each flue direct from the corresponding oven chamber is controlled by a corresponding flow regulator K³ shown as a removable orifice or nozzle member. The regulator K³ is shown as located in the channels K', except that in the case of a channel K' connected to an ascension pipe the member

K³ is mounted in the upper end of the corresponding channel K' as shown in Fig. 3B.

Distillation gases not passed directly to the oven heating flues C pass from the gas collecting space above the charge in each coking chamber, upward through the corresponding ascension pipe L to a gas collecting main LA. The gas discharged through the collecting main LA may be treated for the recovery of byproducts in accordance with customary byproduct practice. However, in some at least of the uses for which the improved oven was primarily designed, it is desirable to avoid the expense of provided byproduct equipment, or to minimize that expense by confining the byproduct recovery treatment to a tar recovery treatment.

When desirable, all of the gas evolved in the oven chambers is withdrawn from the battery through the main LA, and after being treated for the recovery of some byproduct or byproducts, the portion of the gas required for oven heating, is passed into the various flues C. For such operation, communication between the oven chambers A and the gas supply channels J, is cut off as by replacing the orifice members K³ by imperforate plugs. As shown, gas withdrawn from the main LA may be passed into the flues C through the channels J and horizontal pipes M, there being one pipe M for each heating wall. Each pipe M extends transversely of the battery, and is embedded in the masonry adjacent the top of the battery structure, and is connected through branches M' to the upper ends of the various channels J of the heating wall. The supply of gas to each flue C from the corresponding pipe M may be regulated by means of replaceable nozzles or throttling devices such as those disclosed in my prior application for patent Ser. No. 298,526, filed October 9, 1939, now Patent No. 2,273,885.

The battery structure ordinarily, and as shown, is provided with vertical buckstays at the ends of the heating walls held in place by tierods which may be similar to those employed in byproduct coke ovens of standard type, and hence need not be further referred to herein. Distillation gases withdrawn from the battery through the main LA and not returned for use in heating the battery, may be used for any readily available purpose, and in particular, may advantageously be used in some cases, in firing steam generating boilers, and in many cases, also, the waste heating gases discharged from the battery through the tunnel G, may advantageously be used in waste heat steam generating boilers, to provide steam used for power purposes.

As previously indicated, my improved coke oven structure was devised primarily for use in the carrying out of a method devised by me for producing relatively strong and dense coke from a coal, such as Illinois coal, which has an appreciably higher volatile content than any coal or coal mixture heretofore used in the production of metallurgical coke. Said method, which is fully disclosed and claimed in my concurrently filed application Ser. No. 330,048, is characterized in particular by the fact that the coal charge in each retort is initially in the form of a finely ground moist coal mass compressed to such a relatively high density that the weight of the non-volatile content of the charge will be about equal to the weight of the non-volatile content of an equal volume of the less volatile coal charged into a standard type oven for the production of metallurgical coke through open-

ings in the top wall of the oven chamber, or inserted in the oven chamber in the form of a compressed cake.

For the compression of the oven charges, in the practice of my method, I have shown diagrammatically in Fig. 1, a coal compressing or stamping mechanism which may be of one or another of various known forms, but which should be constructed and operated with the strength and power needed to compress the coal cake formed to a density greater than had been customary heretofore. As diagrammatically shown in Fig. 1, the compressing mechanism O is included in a charging and pushing machine which runs on track rails P extending along one side of the battery, and which includes a ram Q for moving the compressed coal cake from the compressing chamber of the mechanism O, into an empty oven chamber A, in front of which the compressing chamber has been positioned, with the corresponding coke oven door A' removed. After the coal charge thus inserted in the oven chamber has been coked, the ram Q may be operated to expel the coke mass from the oven chamber through a coke guide R on to a quenching car or other coke receiver S, located at the opposite side of the battery from the charging and pushing machine.

In the practice of my method, it is ordinarily desirable that the coking charges should be subjected to relatively high temperatures, and to facilitate such high temperature operation, I make the walls between the heating flues C and the adjacent oven chambers A appreciably thinner than the corresponding walls of the standard type ovens used in the production of metallurgical coke. For example in my improved oven, the said flue wall thickness will be about three inches, instead of being from four and one half to six inches, as is customary in the standard type ovens, although the bricks in the walls between the flues and the coking chambers of my oven may be of the same silica brick compositions customarily employed in the heating wall bricks of standard type ovens. Such reduction in the thickness of the walls between the flues C and coking chambers A, reduces the flue temperatures required for the attainment of the desired charge heating effect and final coke temperature, and thus reduces the risk of injurious local overheating of the battery structure. The reduction in flue combustion temperatures thus made possible, also provides compensation for the non-use of highly preheated combustion air.

Notwithstanding the above mentioned reduction in wall thickness, the heating walls of my improved oven have ample strength for their intended use. The highly compressed cake charges of high volatile coal do not swell and ordinarily do not change in shape during the coking operation. Ordinarily, therefore, the heating walls are not subjected to any relatively large thrust by the material within the coking chambers during any stage of the oven charging, coking or discharge operations. This is true, notwithstanding the fact that the coking chambers of my improved oven need not ordinarily be tapered in width from one side of the battery to the other, as is customary with standard type ovens.

Coke ovens, constructed in accordance with the present invention may obviously vary widely in their dimensions, but I note by way of example and illustration, that in the particular coke oven design illustrated in the drawings, each indi-

vidual coking chamber is thirty-three and one-half feet long, eight feet high, and thirteen inches thick, and that each heating wall contains twenty-two heating flues C, and that the compressed coal cake, charged into each oven of the dimensions stated may be twelve inches thick and about seven and a half feet high. The heating flues C are ordinarily identical in form and dimensions, except that I advantageously make the flue width, measured transversely of the battery, substantially less in the case of each heating wall end flue, than in the case of the intermediate flues. For example, in the design shown, the said flue width is eight inches in the case of the heating wall end flues, and is twelve inches in the case of the intermediate flues. By thus diminishing the width of the heating wall end flues, without correspondingly reducing the amount of fuel gas burned in the flues, sufficient heat may be liberated in the end flues to maintain proper temperatures at the ends of the oven chamber, notwithstanding the substantial radiation heat losses at the sides of the battery.

Since the oven chamber and compressed charge are not tapered in width, the heating requirements of all intermediate heating flues are the same, and need not differ from the heating requirements of the end flues when the width of the latter are suitably reduced as described. The similarity in the heat requirements of, and heating gas flow in the different flues, and the character of the fuel gas and combustion air provisions facilitate the attainment of the uniform heat distribution required for high efficiency. The recuperator chambers IA and ia in the brickwork mass below the coking chambers and flues, and above the supporting deck D which forms the ceiling for a subway chamber or air space beneath the battery from which air is drawn into the recuperator chambers, desirably distribute and preheat the combustion air, and prevent the lower portion of the coke oven structure from attaining undesirably high temperatures, without interfering with the proper combustion air distribution or impeding the withdrawal of the waste heating gases.

For further insurance against undesirably high temperatures in the lower portion of the coke oven structure, I may provide cooling ducts T extending longitudinally of the battery in the portion of the coke oven brickwork immediately above the supporting deck D. Those ducts may communicate with the atmosphere at the ends of the battery, and may communicate with the subway air space beneath the battery through passages T' extending vertically through the deck D at one or more points along the length of the battery, and provided, as shown, with flow regulating devices T². As shown each duct T is connected by a small port T³ to an adjacent recuperator chamber IA or ia in each heating wall, so that the battery stack or draft suction constantly draws air through the ducts T. Each of the recuperator chambers IA and ia thus receives air through a main inlet IA' or ia', and through an auxiliary inlet T³. The effective draft suction impressed on the lower end of each flue C, may be regulated by the adjustment of a slide brick U at the bottom of the flue, and adjustable through a corresponding inspection channel in the roof of the flue.

In Figs. 4 and 5, I have illustrated a modified form of my invention, in which some reduction in inherent construction cost and in the vertical dimensions of a battery of given coking capacity,

is secured by omitting the recuperative provisions and the subway air chamber features of the battery shown in Figs. 1, 2 and 3.

In respect to the general form and disposition of the coking chambers A, heating walls B, flues C, sole channels F, and their heating flue connections H and H', the construction shown in Figs. 4 and 5, is similar to that shown in Figs. 1-3. The particular battery construction shown in Figs. 4 and 5, comprises only a few courses of bricks beneath the bottom of the waste heat sole channels F, and is especially adapted for use where the earth beneath the battery is sufficiently strong and stable to permit the battery to have relatively slight and simple foundation provisions.

In the construction shown in Figs. 4 and 5, combustion air is supplied to each flue C at its upper end and at a lower level through conduits *ib* and *IB* receiving air at or adjacent the top of the battery. As shown, the various pipes *ib* and *IB* supplying combustion air to the flues C of each heating wall B, receive air from a fan or other sources (not shown) of air under pressure, through a corresponding transverse air supply pipe W embedded in the oven masonry, adjacent the top of the battery. Between its connections to the corresponding flue C and pipe W, each of the channels *IB* and *ib* may be provided with a measuring orifice nozzle, or other regulating device *W'*. Cooling channels TA are formed in the lower portion of the battery structure for the flow through said channels of atmospheric air.

Aside from the omission of the recuperation and bottom cooling actions in the battery shown in Figs. 1-3, and the need to supply combustion air under pressure, instead of drawing it into heating flues by stack suction, as is ordinarily done with the battery shown in Figs. 1-3, the general operating characteristics of the battery shown in Figs. 4 and 5 are substantially the same as those of the battery shown in Figs. 1-3. In each form of battery shown the fuel gas supplied through the pipes *M*¹ may have some air admixed with it to thereby avoid objectionable carbon deposits in the hot gas distribution channels.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. A waste heat coke oven battery comprising side by side, horizontally elongated, coking chambers, and heating walls alternating with the coking chambers and each formed with vertical heating flues distributed along its length, means for supplying fuel gas to each of said flues at its upper end and for supplying combustion air to each flue at its upper end and at a lower level, and means for withdrawing products of combustion from the lower ends of the different flues comprising a sole channel beneath each coking chamber and in communication with the lower ends of flues alongside said coking chamber and an off-take connection to said sole channel at one side of the battery.

2. A waste heat coke oven battery comprising side by side, horizontally elongated, coking chambers, and heating walls alternating with the coking chambers and each formed with vertical heating flues distributed along its length and separated from one another by flue division walls means for supplying fuel gas to said flues at their upper ends, means including channels formed in the heating walls for passing combustion air upward from the underside of the battery into upper portions of said flues, regulating means for adjustment from the underside of the battery regulating the rates at which combustion air is passed upward through said channels and means comprising horizontal sole channels parallel to and beneath the bottom level of the coking chambers and a waste heat tunnel extending longitudinally of the battery to which said sole channels are directly connected and through which the waste heating gases are withdrawn from said flues and sole channels.
3. A waste heat coke oven battery comprising horizontally elongated, side by side, coking chambers, and heating walls alternating with the coking chambers and each formed with vertical heating flues arranged in a row extending from one end of the wall to the other and separated from one another by flue division walls, means for supplying fuel gas to each flue adjacent its upper end, means for withdrawing heating gases from the lower ends of said flues comprising a sole channel beneath each coking chamber and in communication with the lower ends of adjacent flues and an off-take connection to said sole channel at one side of the battery, and means for supplying combustion air to the upper portions of the different flues, comprising recuperator chambers alongside the sole channels and having air inlets at their lower ends and comprising channels leading upward from said chambers through said flue division walls and opening into the upper portions of said flues.
4. A waste heat coke oven battery comprising horizontally elongated, side by side, coking chambers and heating walls alternating with the coking chambers and each formed with vertical heating flues arranged in a row extending from one end of the wall to the other, and separated from one another by flue division walls, means for supplying fuel gas to said flues adjacent their upper ends and means for supplying combustion air to upper portions of said flues comprising vertical air supply channels each having an intermediate portion in a corresponding flue division wall with an outlet port opening to the upper portion of an adjacent flue and each having end portions extending to the top and bottom sides of the battery, and means for withdrawing heating gases from the lower ends of said flues comprising a sole channel beneath each coking chamber and in communication with the lower ends of adjacent flues.
5. A waste heat coke oven battery comprising horizontally elongated, side by side, coking chambers, and heating walls alternating with the coking chambers and each formed with vertical heating flues arranged in a row extending from one end of the wall to the other and separated from one another by flue division walls, means for supplying fuel gas to each flue adjacent its upper end, means for withdrawing heating gases from the lower ends of said flues comprising a sole channel beneath each coking chamber and in communication with the lower ends of adjacent flues.

ends of adjacent flues, cooling channels extending longitudinally of the battery at the bottom of the latter and beneath, and adapted to absorb heat directly from the bottom walls of said sole channels and open to the atmosphere and means for supplying combustion air to the upper portions of the different flues, comprising recuperator chambers alongside the sole channels and channels leading upward from said chambers through said flue division walls and opening into the upper portions of said flues and comprising means for supplying air to said recuperator chambers including a main air inlet to each chamber opening directly to the atmosphere at the underside of the battery, and an auxiliary air inlet port opening into each chamber from an adjacent cooling channel.

6. A waste heat coke oven battery comprising

5 side by side horizontally elongated, coking chambers, and heating walls alternating with the coking chambers and each formed with vertical heating flues distributed along its length, means for supplying fuel gas to each of said flues at its upper end and for supplying combustion air to each flue at its upper end and at a lower level, comprising vertical channels in said heating wall in communication with the atmosphere 10 at the under side of the battery, and means for withdrawing products of combustion from the lower ends of the different flues, comprising a sole channel beneath each coking chamber and in communication with the lower ends of flues 15 alongside said coking chamber and an off take connection to said sole channel at one side of the battery.

CARL OTTO.
